UNITED STATES PATENT OFFICE.

HERMAN E. CRANDALL, OF NEW BRITAIN, CONNECTICUT.

SUSPENDER BUCKLE AND WEBBING COMBINATION.

1,177,684.

Specification of Letters Patent.

Patented Apr. 4, 1916.

Application filed May 6, 1915. Serial No. 26,244.

To all whom it may concern:

Be it known that I, HERMAN E. CRANDALL, a citizen of the United States, residing at New Britain, in the county of Hartford and State of Connecticut, have invented certain new and useful Improvements in Suspender Buckle and Webbing Combinations, of which the following is a specification.

My invention relates to improvements in suspender buckle and webbing combinations, and the object of my improvement is simplicity and economy in construction and convenience and efficiency in use.

In the accompanying drawing:—Figure 1 is a front elevation in part broken away of my improved suspender buckle. Fig. 2 is a rear elevation of the same. Fig. 3 is a side elevation of the same. Fig. 4 is a sectional view on the line $x-x$ of Fig. 1, 20 with the webbing in place. Fig. 5 is a similar view, showing a different way of threading the webbing. Fig. 6 is a plan view.

My suspender buckle and webbing combination comprises a buckle having means 25 for securing the fixed end of the webbing involving a combined pinching and holding effect and means for clamping the running portion of the webbing, a metal loop 10 for supporting a trouser strap being supported 30 by a fold or loop 11 of the webbing between the said fixed end and the running portion.

The buckle comprises a frame of wire having a bar 12 at the upper end and a clamping lever pivotally supported on the 35 said bar by means of hinge sleeve members 13, having a clamping lip 14 on one side of the said sleeve member 13, provided with a serrated edge, and a handle 15 on the other side thereof.

40 The frame as stated is made of wire and the bar 12 is at the middle portion thereof.

From the ends of the bar 12 the wire is brought rearwardly by an open return bend, providing cross-connected and spacing loops 45 16 at the said ends. From the rear arms of the loops 16 the wire is brought inwardly, generally in parallelism with the bar 12 for an appreciable distance, forming a pair of short bars 17 in alinement. At the inner 50 ends of the short bars 17 there is in each case an open downwardly directed return bend or loop 18, supporting outwardly directed lower short arms 19, which are parallel with the upper short arms 17. At 55 the outer ends of the lower short arms 19

there is a second downwardly directed open return bend 20, the lower arms of which serve as coöperating spring members of bar-like form. The said spring members or bars extend from the loop 20 almost but not entirely across the width of the frame, each terminating slightly inwardly from the loop 20 that supports the mating spring member, as will be noted from Figs. 1 and 2, and are of less width than the width of the 60 webbing.

Considering Fig. 1, the spring arm 21 supported by the right hand lower loop 20 extends to the left, parallel with the bar 12, and terminates appreciably inwardly of 70 the lower loop 20 at the right, as may be best seen in Fig. 2. The spring arm 22, supported by the left hand lower loop 20 extends from the said loop to the right, in abutment with the mating spring arm 21, or 75 separated therefrom by the webbing when in use, and the free end 23 is given an outward bend to form with the opposed portion of the mating spring arm 21 a V-shaped entrance mouth, to facilitate entering the 80 webbing between the two spring arms, and also forming a prong-like projection for embedding itself in the webbing.

The webbing may be applied to the buckle in various ways, two of which are shown. 85

Considering Fig. 4, the webbing is inserted between the spring arms 21 and 22, with the raw end above the said arms. Then the webbing is bent around the spring arm 22 as shown at 24 and brought upwardly over the upper short arms 17, as shown at 25. The latter short arms 17 serve essentially as an interrupted bar, suitable to receive the webbing in the manner described. Passing over the upper side of the 90 said interrupted bar, 17, 17, the webbing drops downwardly to form the rear arm or reach 26 of the loop 11 already mentioned, the front reach 27 thereof passing upwardly over the fold or loop 22 of the webbing on 100 the spring arm 22 and under the clamping lip 14, thence upwardly to form the main supporting reach or body portion 28.

In the arrangement shown in Fig. 5 the webbing is inserted between the spring 105 arms 21 and 22 with the raw end 29^a directed downwardly. Passing from the said raw end 29^a upwardly between the spring arms 21 and 22 the webbing passes directly over the interrupted bar 17, 17, as shown 110

at 25^a and then downwardly to form the loop 11 and under the clamping lip 14 as in the other arrangement described.

The portion of the frame that coöperates with the clamping lip 14 in clamping the running portion of the webbing is some part of the wire material adjacent the upper rear return bends 18. That is to say, in forming the said upper, rear return bends 10 or loops 18 the material is brought inwardly sufficiently to coöperate with the clamping lip 14, and particularly with the lateral edge portion thereof. As shown, the loops 18 are appreciably separated, and the 15 amount of such separation may be varied as desired. The two return bends or loops 18 constitute essentially the body portion of the frame, the end connections 16 at the upper ends serving with the bar 12 to form 20 a loop for admitting the webbing with the proper spacing for the bar 12, and to provide a pivotal support by means of the bar 12 for the clamping lever, and the lower end bends 20 providing supports for the 25 spring arms 21 and 22.

It is apparent that some changes from the specific construction herein disclosed may be made, and therefore I do not wish to be understood as limiting myself to the 30 precise form of construction shown and described, but desire the liberty to make such changes, in working my invention, as may fairly come within the spirit and scope of the same.

35 I claim as my invention:—

1. A suspender buckle comprising a frame and a clamping lever mounted thereon, the 40 said frame being made of a piece of wire, the middle portion of the said wire being in the form of a bar and serving as a pivotal support for the said lever, the portions intermediate the said middle portion and the 45 end portions being bent suitably to form the body portion of the frame and to serve as a clamping member in coöperation with the said lever, and the two end portions being also each of barlike form, extending inwardly from opposite sides of the frame, and overlapping one another for substantially their entire lengths suitably to serve 50

as spring members for coöperating to clamp a webbing interposed therebetween.

2. A frame for a suspender buckle formed of a piece of wire, the body portion of the 55 said wire being bent suitably to form the body portion of the said frame, and the two end portions of the said wire being supported from opposite sides of the frame and extending inwardly from the junctions with the said frame, in parallelism and overlapping one another, and each terminating in a free end adjacent the junction of the other member with the frame, whereby the overlapping portions of the said wire serve as 60 coöperating spring clamping members for 65 clamping a webbing interposed therebetween.

3. A frame for a suspender buckle formed of a piece of wire, the body portion of the 70 said wire being bent suitably to form the body portion of the said frame, and the two end portions of the said wire being supported from opposite sides of the frame and extending inwardly from the junctions with the said frame, in parallelism and overlapping 75 one another, and each terminating in a free end adjacent the junction of the other member with the frame, and the extreme end of one of the said end portions being bent away from the opposed other end portion suitably to form a mouth for receiving 80 the edge portion of the webbing.

4. In a suspender buckle, a frame and a pair of coöperating clamping members for pinching the end of the webbing formed 85 of a single piece of wire, the body portion of the said wire being bent to form the said frame and the end portions of the said wire serving as the said clamping members, extending from the said frame in overlapping 90 engagement suitably to pinch a webbing interposed therebetween, whereby the entire portion of the said wire that forms the said frame serves also as a spring member to hold the said end portions in resilient engagement. 95

HERMAN E. CRANDALL.
